FIGURE 1 is a perspective view of a condiment cup or similar article, showing my new design,

The essential feature of my design resides in the combination of the particular peripheral lip configuration with a condiment cup of the particular configuration and proportions shown.

I claim:

The ornamental design for the condiment cup, as shown and described.
